EXPLOSIVE CARTRIDGE UNIT

Lewis B. Counterman, Kenvil, N. J., assignor to
 Hercules Powder Company, Wilmington, Del.,
 a corporation of Delaware

Application April 19, 1946, Serial No. 663,297

7 Claims. (Cl. 102—24)

1

This invention relates to explosive cartridges and, more particularly, to an explosive cartridge unit which is adaptable to use in the seismograph blasting art.

Heretofore in seismograph blasting two procedures have been followed. In accordance with one procedure, it has been customary to place in the drilled hole a plurality of explosive cartridges attached together in various ways as, for example, by attachment to a relatively long stick of wood. This method is tedious and time consuming, and otherwise undesirable.

It has also been proposed to use an ammonium nitrate explosive in a sheet metal cartridge, these cartridges being provided at their ends with threads so that the assembly can be made by interthreading a number of these cartridges. In order to explode the assembly thus produced, there is screw-threadedly attached at a point in the column a priming charge in the form of a special cartridge of trinitrotoluene or amatol (a mixture of trinitrotoluene and ammonium nitrate) which is provided with a blasting cap. This method is disadvantageous because the metal containers are expensive to manufacture and unduly increase the handling cost. Moreover, the use of a relatively heavy metal container unduly lowers the percentage by weight of actual explosive in the unit. In addition, the length of the metal cartridge shell is limited to about 8 inches because of manufacturing difficulties, whereas paper cartridges may be made in any length up to the maximum allowed by I. C. C. shipping regulations.

In U. S. 2,317,415, there is disclosed the provision of a cartridge of explosive with a slideable frictionally held sleeve surrounding it, this sleeve being slideable along the cartridge into corresponding frictional engagement with an adjacent cartridge placed in end-abutting relationship to the first-named cartridge. In this manner, a standard unit is provided which is readily built up by the operator into an explosive column of any desired length. Difficulty arises in the use of telescoping cartridges of this type because there is frequently a tendency for the adjacent cartridges to slip apart from one another as the column is lowered into a vertical borehole.

It is an object of the present invention to overcome this difficulty with the telescoping cartridges described in U. S. 2,317,415 while at the same time attaining all of the advantages of such telescoping cartridges over the prior art practices outlined briefly above.

Another object is to provide a single cartridge unit which can be quickly associated with one or

2

more units, identical therewith, to build up a seismograph blasting assembly of the desired length and explosive effect.

It is another object to provide an explosive cartridge unit useful in the seismograph blasting art which contains more explosive per unit of volume and more explosive per unit of weight than the metal assembly made as described above.

Other objects of the invention will appear hereinafter, the novel features and combinations being set forth in the appended claims.

These objects are obtained in accordance with the present invention of an explosive cartridge unit by providing for interlocking engagement between the connecting sleeve, which extends across the joint between adjacent cartridge units, and the cartridges themselves. It is preferred to provide circumferential abutments on the exterior near each end of the cartridge and on the interior wall near each end of the connecting sleeve. One end of the sleeve is preferably in locked telescoping assembly to the cartridge and the other end adaptable to being brought into locked engagement with a similar cartridge unit.

25 A preferred embodiment of this invention is illustrated in the drawing wherein like numbers refer to like parts wherever they occur.

Fig. 1 is an isometric elevational view of the cartridge unit in partial section showing the preferred embodiment of the invention in a position preparatory to connection with a like cartridge unit, a portion of which is shown;

30 Fig. 2 is an isometric elevational view in partial section showing the invention of Fig. 1 in locked assembly to a like unit to form a columnary explosive assembly;

35 Fig. 3 is an isometric elevational view in partial section of an alternative embodiment of the sleeve portion of the invention.

40 With reference to the drawings, an explosive cartridge 10, packed with explosive, may be of the usual tubular paper wrapped type. Slidably and telescopically mounted upon the cartridge 10 and in close fitting relationship thereto, is a connecting sleeve 11.

45 A leading collar 12 and a retaining collar 13 formed on the cartridge 10 serve as abutment means for the slideable collar 14 formed on the connecting sleeve 11 and limit the axial movement of said sleeve.

50 Slots 15 permit sufficient expansion of the open end of the connecting sleeve 11 and a locking collar 16 formed on the interior peripheral portion thereof to allow passage of the leading collar 17 on an explosive cartridge 18 of a like unit

to a position of abutment between the locking collar 16 and the end of the cartridge 10 as shown in Fig. 2. Although a plurality of slots 15 is preferred, a single slot is operable. After assembly in this position, a sliding sleeve 19 may be moved over the slots 15 and in abutment with a stop collar 20 to lock the locking sleeve 11 over the inserted cartridge 18. The stop collar 20 prevents dislodgement of the sliding sleeve 19 when an explosive column made up of units described above is lowered down a drilled hole.

An alternative construction of a locking connecting sleeve 21 as shown in Fig. 3 is provided with slots 22 at both ends and sliding sleeves 23, slideable over said slots to prevent expansion of the slotted ends of the sleeve after integral locking collars 24 are assembled in locking abutment with the collars of the cartridges as described above. Although a plurality of slots 22 at each end of the locking connecting sleeve 21 is preferred, a single slot at each end is operable. When the sleeves are constructed in this manner, the cartridges may be manufactured independently of the sleeves.

The explosive cartridge units constructed in accordance with the invention were found to function very satisfactorily. Upon assembly of the units to make up a column of explosive, an extremely strong and rigid structure, especially useful in seismograph construction, was quickly assembled. The prevention of mud, dirt or debris from getting between the separate cartridges as they were lowered as a column in the borehole was an important advantage as well as the ability of the column to remain intact under conditions of high tensile stress.

What I claim and desire to protect by Letters Patent is:

1. An explosive cartridge unit adapted to be connected to a similar unit comprising a cylindrical explosive cartridge; a leading collar formed on the exterior peripheral portion of one end of said cartridge; a retaining collar formed on the exterior peripheral portion of said cartridge and on the end opposite to said leading collar; a hollow cylindrical connecting sleeve; a slideable collar formed on the interior peripheral portion of said sleeve and slideably retained on the cartridge between said leading and retaining collars; a locking collar formed on the interior peripheral portion of said sleeve which extends substantially beyond said cartridge and on the end opposite said slideable collar; a slot substantially parallel to the central axis and extending from the projecting end of said sleeve to a point forward of the locking collar; a sliding sleeve slideably mounted on the connecting sleeve and adapted to be positioned over said slots; and a stop collar whereby the movement of said sliding sleeve is limited.

2. An explosive cartridge unit adapted to be connected to a similar unit comprising a cylindrical explosive cartridge; a leading collar formed on the exterior peripheral portion of one end of said cartridge; a retaining collar formed on the exterior peripheral portion of said cartridge and on the end opposite to said leading collar; a hollow cylindrical connecting sleeve; a slideable collar formed on the interior peripheral portion of said sleeve and slideably retained on the cartridge between said leading end retaining collars; a locking collar formed on the interior peripheral portion of said sleeve which extends substantially beyond said cartridge and on the end opposite said slideable collar; a plural-

ity of slots substantially parallel to the central axis and extending from the projecting end of said sleeve to a point forward of the locking collar; a sliding sleeve slideably mounted on the connecting sleeve and adapted to be positioned over said slots; and a stop collar whereby the movement of said sliding sleeve is limited.

3. An explosive cartridge unit comprising a cylindrical explosive cartridge; a collar formed on the exterior peripheral portion near each end of said cartridge; a hollow cylindrical connecting sleeve; attachment means comprising a collar formed on the interior portion and near one end of said connecting sleeve, and slideably retained on the cartridge between the collars formed on said cartridge; and locking means for lockable attachment of said connecting sleeve to the cartridge of a similar explosive unit.

4. An explosive cartridge unit comprising a cylindrical explosive cartridge; a collar formed on the exterior peripheral portion near each end of said cartridge; a hollow cylindrical connecting sleeve; attachment means for slideable and telescopic attachment of the connecting sleeve to said cartridge; and locking means for lockable attachment of said connecting sleeve to the cartridge of a similar explosive unit, said locking means comprising a slotted interior member formed on an interior peripheral portion of the connecting sleeve which extends substantially beyond the cartridge; a plurality of slots in the body of the connecting sleeve substantially parallel to the central axis thereof and extending inwardly from the projecting end of said sleeve to a point beyond the interior locking member, said slots being in alignment with the slots in the interior member; an exterior sliding sleeve slideably mounted on the connecting sleeve and adapted to be positioned over said slots; and means mounted on the end of the connecting sleeve, whereby the movement of said sliding sleeve is limited.

5. An explosive cartridge connecting sleeve comprising a tubular sleeve; slotted internal locking members formed on the interior peripheral portions near each end of said sleeve; a plurality of slots in the body of the tubular sleeve substantially parallel with the central axis thereof and extending from the ends of said sleeve toward its midpoint to a distance in excess of the length of said locking members, said slots being in alignment with the slots in the locking members; and a plurality of sliding sleeves mounted on the tubular sleeve and positionable over said slots.

6. An explosive cartridge unit comprising a cylindrical explosive cartridge; a collar formed on the exterior peripheral portion near each end of said cartridge; a hollow cylindrical connecting sleeve; attachment means for slideable and telescopic attachment of the connecting sleeve to said cartridge; and locking means for lockable attachment of said connecting sleeve to the cartridge of a similar explosive unit; said attachment means and said locking means comprising slotted internal locking members formed on the interior peripheral portions near each end of said sleeve; a plurality of slots in the body of the tubular sleeve substantially parallel with the central axis thereof and extending from the ends of said sleeve toward its midpoint to a distance in excess of the length of said locking members, said slots being in alignment with the slots in the locking members; and a plurality of sliding

sleeves mounted on the tubular sleeve and positionable over said slots.

7. An explosive cartridge unit comprising a cylindrical explosive cartridge; a collar formed on the exterior peripheral portion near each end of said cartridge; a hollow cylindrical connecting sleeve; attachment means for slidable and telescopic attachment of the connecting sleeve to said cartridge, said attachment means comprising a raised member formed on the interior peripheral portion adjacent the end of the sleeve; and locking means disposed at the end of the sleeve opposite the attachment means for lockable attachment of said connecting sleeve to the cartridge of a similar explosive unit, said locking means comprising a slotted interior member formed on an interior peripheral portion of the connecting sleeve which extends substantially beyond the cartridge; a plurality of slots in the body of the connecting sleeve substantially parallel to the central axis thereof and extending inwardly from the projecting end of said sleeve to a point beyond the interior locking member, said slots being in alignment with the slots in the interior member; an exterior sliding

20

25

sleeve slidably mounted on the connecting sleeve and adapted to be positioned over said slots; and means mounted on the end of the connecting sleeve, whereby the movement of said sliding sleeve is limited.
